UNITED STATES PATENT OFFICE.

SIGMUND DEICHES, OF CHICAGO, ILLINOIS.

NECKTIE.

Application filed November 20, 1922. Serial No. 601,995.

To all whom it may concern:

Be it known that I, SIGMUND DEICHES, a citizen of the United States, and a resident of Chicago, Cook County, and State of Illinois, have invented certain new and useful Improvements in Neckties, of which the following is declared to be a full, clear, and exact description.

This invention relates to neckties, and more particularly to the ready made bow type of neckties. The object of this invention is to provide a light, flexible shape holder for the tie, which will retain it in shape, but which may be readily bent with the fingers to alter the position of the bows or wings of the tie to suit the taste of the wearer. To such ends this invention consists in the several novel features hereinafter fully set forth and claimed.

20 The invention is clearly illustrated in the accompanying drawing, in which:

Fig. 1 is a perspective view of a bow tie embodying a simple form of the present invention; Fig. 2 is a rear face view laid out flat, of the two members of the part which forms the front wings or bows; Fig. 3 is a rear face view of said part after it has been partly folded preparatory to being assembled with the other parts; Fig. 4 is a front view of the parts showing the middle portion of the bows or wings gathered together with the loop portion in place before being sewed thereto; Fig. 5 is a longitudinal section through the finished tie and Fig. 6 is a vertical cross section through the shape holder.

Referring now to said drawing, which illustrates one embodiment of the invention, the reference character 10 designates the bow portion of a bow necktie, and 11 the elastic band which is secured to its rear side and contains the usual fastening means 12 for securing it upon the collar.

The bow portion 10 comprises a front wing portion 13, a back wing portion 14, and a band 15 which is wrapped around the middle of the wing portions 13, 14, and sewed thereto, as is customary.

The front wing portion 13 comprises a rectangular piece of necktie material 16, of the proper size and shape to form the front wings. Placed against this piece at its middle portion, is the shape holder A, which comprises a rectangular envelope 17, preferably composed of a canvas or the like in which is contained a rectangular wire loop

20. The envelope 17 may be formed from a strip of canvas folded upon itself and stitched together along the side and end edges by rows of stitches 18. Rows of 60 stitches 19, parallel to the stitches 18 and spaced inwardly on the envelope, are made therein to form a rectangular pocket 27 having four narrow sides in which the rectangular wire loop 20 is confined. The wire loop 65 and envelope are thereby secured together throughout the entire length of the wire so that when the wire is bent at any place in any direction, the envelope at that place will also be bent in the same way, and since the 70 shape holding member is contained in the front wing portion, the latter will be correspondingly bent and will be held in such bent condition until bent into some other shape. The loop 20 is made of light gauge, 75 pliable and easily bent wire, which, when bent into any shape, holds that shape until bent into some other shape.

In forming up the front wing portion, the top and bottom portions 21, 22 of the material 16 are folded down on the shape holder A, along the lines 23, 24, and sewed to the envelope 17 as at a, in Fig. 3. The end portions 25 are then folded down upon the rest, along the lines 26. The back piece 14, 85 which is of the same size and shape as the front piece 13, is then folded up in the same manner.

The front and back folded pieces 13, 14 are placed together, with the folded edges 90 placed back to back, and the loop portion 15 is wrapped tightly around them at the middle, and sewed thereto at the back. The elastic band 11 is attached at the back between the loop and back piece, as is well 95 understood.

Normally, the two front bows or wings will be held in a flat condition, but if the wearer wishes to have the bows or wings stand at an angle to each other, or to assume any artistic shape, he bends the front wings into the desired shape, and the wire staying loop thereupon holds the wings in such bent positions. In Fig. 1 the bows of the front piece 13 are shown in their flat condition in full lines and in outwardly bent condition in dotted lines. Fig. 5 also shows the front wings bent forward in solid lines, and bent into irregular form by the dotted lines.

The wire loop effectively retains the bows in any shape into which they are bent. The

- ends of the wire loop hold the outer ends of the wings or bows in their normal smooth condition, and the parts of the wire loop that are bent, in bending the bows, hold 5 the bows in such bent condition, thereby giving a more artistic and pleasing appearance to the tie. The envelope which contains the wire loop and acts as a filler for the tie, and the wire of the loop being confined in the 10 narrow pockets, it positively shapes the envelope to any form into which the wire is bent. The wire can not get out of place in the envelope, but is confined therein along its entire length.
- 15 I claim as new and desire to secure by Letters Patent:
1. In a bow necktie, folded front and back wing pieces, a closed fabric envelope con-
  - tained in the front piece and conforming to the shape thereof, a bendable, rectangular wire loop contained in said envelope and conforming to the shape thereof, and a band around the middle of said wing pieces. 20
  2. In a bow necktie, a folded front wing piece, a fabric envelope contained therein and having a narrow four sided pocket formed therein, and a rectangular bendable wire loop confined in said four sided pocket. 25
  3. In a bow necktie, a folded front wing piece, a fabric envelope contained therein and stitched thereto, said envelope having parallel rows of stitches forming a four sided pocket, and a rectangular bendable wire loop confined in the four sides of said pocket. 30

SIGMUND DEICHES.
